UNITED STATES PATENT OFFICE.

EARL D. RADER, OF BEDFORD TOWNSHIP, WESTCHESTER COUNTY, NEW YORK, AS
SIGNOR TO DEXTER FOLDER COMPANY, OF NEW YORK, N. Y., A CORPORATION OF
NEW YORK.

SHEET-COMBING FEEDING MACHINE.

Application filed September 6, 1923. Serial No. 661,235.

The main object of the present invention is to improve the operation of automatic sheet combing feeding machines by providing a protector that operates between the 5 combing instrument and the pile of sheets to soften the action of the combing instrument upon the sheets. This is particularly desirable in feeding printed sheets of high grade, especially freshly printed sheets 10 which are sometimes marred or smutted by the action of the sheet combing instrument. The protector is in the form of a strip or web of flexible material that is presented freely between the combing instrument and 15 the top of the pile of sheets acted upon, so as to be unrestrained and free to respond to the action of the combing instrument. Any suitable flexible material that will transmit the fanning out action of the combing instrument may be employed, but in practice I have obtained the best results with a thin 20 strip or web of woven material such as linen or cotton. The interposition of the protector of flexible material between the combing instrument and pile preserves and prevents smutting the printed surfaces of the 25 sheets acted upon, and at the same time does not interfere with the effective action of the combing instrument.

30 A second feature of the present invention is the provision of a pile side guide with adjustable spring blades acting downwardly upon the top of the pile at opposite sides, so as to equalize the tension upon the sheets and 35 insure an even feeding movement of the sheets from the pile. This improvement in the pile guides is particularly important in feeding heavily printed sheets with which there is sometimes a tendency for uneven 40 movement from the pile because of the unequal distribution of the printed surfaces.

In order that the invention may be fully understood, I will first describe the same with reference to the accompanying drawings and afterward point out the novel features in the annexed claims.

In said drawings:—

Figure 1 is a vertical longitudinal sectional elevation of part of an automatic sheet combing feeding machine having my improvements applied thereto.

Figure 2 is a detail plan view of parts of the same.

Figure 3 is a vertical transverse sectional

view taken on the line 3—3 of Figures 1 55 and 2.

Figure 4 is an enlarged detail perspective view of a part of the flexible protector and the clamp for attaching it to its supporting rock arm or controller.

Figure 5 is a detail perspective view of the improved pile side guide.

The present improvements may be applied to any sheet combing feeding machine in which the action of the combing instrument can be applied to a pile of sheets through the flexible protector. For the purpose of illustrating the invention it is shown applied to the type of automatic feeder forming part of the combined folding and feeding machine covered by my application filed August 10th, 1923, Serial No. 656,734. The parts of this feeder will only be referred to in a general way sufficient to bring out the operation of the present invention.

In the drawings a machine frame indicated at 1 carries the automatically operated pile supporting table 2 carrying a pile of paper sheets 3. 5 indicates the under feed roller and 6 the usual periodically operated drop rollers constituting the delivery from the pile. 7 is a sheet actuated trip controlling the operation of the sheet combing wheels 8 carried upon a vertically rocking frame 9 and driven through suitable mechanism, not shown, to be periodically raised and lowered and also to be automatically raised in the manner well understood in this art.

10 is a frame bar projecting rearwardly from the machine frame above the pile of sheets 3. This bar 10 carries the automatic tail grip 11, which is operated by the mechanism fully set forth in the above named application.

15 is a strip or web of flexible material which is designed to be presented between the combing wheels 8 and the top of the pile of sheets 3. This piece of flexible material 15 is referred to as a protector because it 100 softens the action of the combing wheels upon the printed surface of a sheet and thereby prevents smutting or other marring of the printed sheet. The protector 15 may be of any suitable material that will produce 105 the desired result without interfering with the transmission of the combing action to the pile operated upon. A strip of cotton or

linen has been found particularly effective for this purpose.

For the purpose of properly presenting the protector of flexible material upon the top of the pile beneath the combing instrument, I provide a controller or rock arm 20 which is freely pivoted upon a stud 21 carried by a channeled bracket 22, which is adjustably mounted upon the rearwardly projecting frame bar 10 above the pile support 2 in the rear of the combing instrument 8. This controller or rock arm 20 carries in its lower end a laterally projecting clamp comprising a recessed bar 25 and a complementary blade 26 fitting thereon and secured thereto by removable set screws 27 which pass through openings in the blade 26 and are threaded into the bar 25. The rear edge of the strip or web of flexible material 15 is attached to the clamp 25, 26 by being placed between these two members and fastening the clamp by means of set screws. The protecting strip can be adjusted in the clamp to cause it to project the desired distance forwardly beneath the combing wheels, it being desirable to have the strip project a little beyond the combing wheels and have a sufficient surface of material to the rear to insure the unrestrained free action of the projecting strip under the action of the combing wheels. To this end the controller arm 20 is so operated as to present a loose buckle or loop indicated at 15^a in the projecting strip just prior to the action of the combing wheels.

The controller arm 20 projects above its pivot 21 and has pivoted to its upper end a rod 30, pivoted at 31 to a bell crank lever 32 journalled upon stud 33 and carrying anti-friction roller 34, which operates upon cam 35 secured to the main cam shaft 36 of the feeder. An adjustable torsion spring 37 mounted upon the stud 33 engages the bell crank lever 32 at 38 to cause the anti-friction roller 34 to follow cam 35.

By the described mechanism the controller or rock arm 20 is caused to periodically rock from its position shown in the full lines to its position shown in the dotted lines in Figure 1, with the result that immediately after each combing action the flexible protector 15 will be drawn rearwardly and restored to its initial or normal position and immediately after this restoring action the controller 20 is moved forwardly to form the free loop or buckle 15^a in the protecting strip to thereby present the protecting strip in unrestrained relation upon the top of the pile, preparatory to lowering the combing wheel for a combing action.

In this type of feeder it is customary to employ pile side guides which are supported upon rearwardly projecting bars 40 and presented upon opposite sides of the pile being operated upon. 45 is such a pile guide

mounted upon the lower end of a rod 46 supported in a socketed bracket 47 carried by bar 40. This side guide 45 preferably constructed as shown in detail in Figure 5 in which it is formed at its upper edge with an inwardly presented flange 45^a, to which is secured by riveting or otherwise the rear edge of a blade 50 of spring steel. An adjusting screw 51 is threaded through bracket 45^a in position to engage the spring blade 50 for adjusting its forwardly presented end upwardly and downwardly upon the pile guides 45. These pile guides 45 are so positioned at the upper side edges of the pile of sheets that they will assist in keeping the sheets straight as they are fed from the pile. In feeding heavily printed sheets difficulty is sometimes encountered because of the tendency of the sheets to move unequally from the pile. This uneven feeding tendency is corrected with the improved pile side gauge by properly adjusting the spring blades 50 to engage the upper sheets with more or less tension, thereby retarding the side of the sheet which tends to move more freely and causing an equalizing effect, with the result that the sheets pass squarely from the pile.

I claim:—

1. The combination with a support for a pile of sheets, and a sheet combing instrument arranged to periodically move into and out of action upon said pile, of a strip or web of protecting material interposed between said instrument and the pile of sheets with freedom to move under the action of the combing instrument.

2. The combination with a support for a pile of sheets, and a sheet combing wheel mounted to move toward and away from and act upon said pile, of a protector of flexible material interposed between said combing wheel and the pile of sheets with freedom to move under the action of the combing wheel.

3. The combination with a support for a pile of sheets, and a sheet combing instrument arranged to act upon said pile, of a protector of flexible material interposed between said instrument and the pile of sheets, and supporting means for presenting a free loop or buckle in the protector in rear of the combing instrument.

4. The combination with a support for a pile of sheets, and a sheet combing instrument arranged to act upon said pile, of a protector of flexible material interposed between said instrument and the pile of sheets and freely movable upon the pile under the action of the combing instrument, and means for periodically returning said flexible material to its normal position.

5. The combination with a support for a pile of sheets, and a periodically acting sheet combing instrument arranged to act upon said pile, of a periodically shifted strip or web of protecting material interposed be-

tween said instrument and the pile of sheets and freely movable upon the pile under the action of the combing instrument, and means for periodically returning said protecting material to its normal position while the combing instrument is out of action.

6. The combination with a support for a pile of sheets, and a sheet combing wheel arranged to act upon said pile, of a protector of flexible material interposed between said combing wheel and the pile of sheets and freely movable upon the pile under the action of a combing wheel, and means for periodically returning said protector to its

15 normal position while the combing wheel is out of action.

7. The combination with a support for a pile of sheets, and a sheet combing instrument arranged to act upon said pile, of a strip or web of flexible woven fabric interposed between said instrument and the pile of sheets and freely movable upon the pile under the action of the combing instrument, and means for periodically returning said

25 flexible woven fabric to its normal position, while the combing instrument is out of action.

8. The combination with a sheet combing instrument adapted to act upon a pile of sheets, of a protecting strip or web adapted to be interposed between the combing instrument and a pile with freedom to move under the action of the combing instrument.

9. The combination with a sheet combing instrument adapted to act upon a pile of sheets, of a strip or web of flexible material, and means for supporting said flexible material between the combing instrument and a pile with freedom to move under the action of the combing instrument.

10. The combination with a sheet combing instrument adapted to act upon a pile of sheets, and means for periodically moving said combing instrument into and out of engagement with the pile, of a protecting strip or web interposed between said instrument and the pile, and a movable controller for said strip or web permitting its unrestrained movement under the action of the combing instrument and acting to restore the protecting strip or web to normal position when the combing instrument is out of action.

11. The combination with a sheet combing instrument adapted to act upon a pile of sheets, and means for periodically moving said combing instrument into and out of engagement with the pile, of a strip or web of flexible material interposed between said instrument and the pile, a movable controller for said flexible material mounted above said pile support in rear of said combing instrument, and means for operating said controller moving it rearwardly and forwardly to first restore the flexible material to normal

position and then establish a free loop or buckle in the flexible material while the combing instrument is out of action.

12. The combination with a periodically acting sheet combing instrument adapted to act upon a pile of sheets, of a protecting strip or web of flexible material, and a controller for said strip or web arranged to present the same between said combing instrument and the pile with a free loop or buckle between the controller and pile, said controller being timed to restore the strip or web to normal position while the combing instrument is out of action.

13. The combination with a support for a pile of sheets, means for delivering sheets from the pile, and a periodically acting sheet combing instrument arranged to act upon the pile, of a protector of flexible material presented freely between said combing instrument and the pile, and a controlling member adapted to periodically restore said protector to its normal position upon the pile.

14. The combination with a support for a pile of sheets, and a periodically acting sheet combing instrument arranged to act upon the pile, of a strip or web of flexible material presented between said combing instrument and the pile, and a periodically operating rock arm mounted above the pile support and having said strip or web attached to it.

15. The combination with a support for a pile of sheets, and a periodically acting sheet combing instrument arranged to act upon the pile, of a strip or web of flexible material presented between said combing instrument and the pile, and a cam operated rock arm mounted above the pile support and having said strip or web attached to it.

16. The combination with a support for a pile of sheets, and a periodically acting sheet combing instrument arranged to act upon the pile, of a strip or web of flexible material presented between said combing instrument and the pile, and a periodically operating rock arm adjustably mounted above the pile support and having means for engaging said strip or web of flexible material.

17. The combination with a support for a pile of sheets, and a periodically acting sheet combing instrument arranged to act upon the pile, of a strip or web of flexible material presented between said combing instrument and the pile, a bar projecting above said pile support, a periodically operating rock arm mounted upon said bar, and means upon said rock arm for attaching said strip or web thereto.

18. The combination with a support for a pile of sheets, and a periodically acting sheet combing instrument arranged to act upon the pile, of a strip or web of flexible material presented between said combing instrument

and the pile, a bar projecting above said pile support, a periodically operating rock arm mounted upon said bar, and a clamp upon said rock arm for engaging said strip 5 or web of flexible material.

19. The combination with a support for a pile of sheets, and means for feeding sheets from the pile, of a pile guide comprising a

plate adapted to engage the edge of a pile, a downwardly acting spring blade mounted 10 upon said plate and engaging the top of the pile adjacent thereto, and an adjusting screw carried by said guide plate and engaging said spring blade.

EARL D. RADER.
